UNITED STATES PATENT OFFICE.

ALFRED BENEDEK, OF NEW YORK, N. Y.

DESIGN FOR A RUBBER BATH MAT.

Application filed July 12, 1923. Serial No. 6,769. Term of patent 7 years.

To all whom it may concern:

Be it known that I, ALFRED BENEDEK, a citizen of the United States, and a resident of Manhattan, in the city, county, and State of New York, have invented a new, original, and ornamental Design for Rubber Bath Mats, of which the following is a specification, reference being had to the accompanying drawing, forming part thereof.

The figure is a plan view of a section of a rubber bath mat showing my new design. I claim:

The ornamental design for a rubber bath mat, as shown.

ALFRED BENEDEK.
